UNITED STATES PATENT OFFICE

112,347

DESIGN FOR A COMBINED CAKE CONTAINER AND SERVING TRAY

Carl G. Nesbitt, New York, N. Y.

Application July 1, 1938, Serial No. 78,209

Term of patent 14 years

To all whom it may concern:

Be it known that I, Carl G. Nesbitt, a citizen of the United States, residing at New York city, New York, in the county of New York, State of New York, have invented a new, original, and ornamental Design for a Combined Cake Container and Serving Tray, of which the following is a specification, reference being had to the accompanying drawing, forming part thereof.

In the drawing—

I claim:

The ornamental design for a combined cake container and serving tray, as shown.

CARL G. NESBITT
